PROCESS OF MAKING LASTED SHOES WITH
FLANGED INSOLES

Arthur E. Kleven, Augusta, Maine

Application November 27, 1951, Serial No. 258,437

2 Claims. (Cl. 12—142)

This invention comprises a new and improved shoe having a flanged insole and includes within its scope the novel shoemaking process of its production.

While the invention has a broad application to the manufacture of shoes or sandals of various types, as will be pointed out hereinafter, its most important field of use is that of shoes in which the upper is preformed accurately in contour to a sole member and then united thereto off the last, the last being subsequently inserted before the bottoming operation is completed.

The process of the present invention has important advantages from the standpoint of economy. It eliminates many of the heretofore conventional shoemaking operations and substantially reduces the length of time the last is tied up in the individual shoe. Heretofore the manufacturer has been obliged to sacrifice the fine lines of quality shoemaking and stylish appearance of the product in order to secure the advantages of economy. The present invention, however, while preserving all the advantages of slip lasting economy, makes possible the production of shoes having all the appearance of the finest shoes heretofore produced by the McKay, Compo or welt processes.

The process of my invention is characterized by the steps of attaching a flexible upstanding wall or flange to the peripheral edge portion of a flat insole, uniting the inner marginal edge portion of a closed upper to the outer surface of the wall in substantially flush relation and with the wall directed outwardly or at right angles to the insole, then inserting a last into the upper, and subsequently folding the wall and the cemented edge portion of the upper inwardly as a unit and securing it to the outer surface of the insole.

The construction of the rib is of secondary importance so long as it is sufficiently stiff to maintain an upright position at substantially right angles to the surface of the insole and sufficiently flexible to be folded smoothly inwardly carrying with it the margin of the upper so that it may be cemented or otherwise secured to the insole. The best procedure now known to me for forming the upstanding wall is to employ a binding strip of textile material folded upon itself and provided with attaching flanges which may be adhesively secured to the opposite flat faces of the insole. When this wall or flange is folded inwardly with the marginal portion of the upper that has been secured to it, the upper is in effect subject to a very substantial lasting operation, that is, the entire margin of the upper is drawn forceably inwardly over the last bottom and secured in place

under substantial lasting tension. In this step it will be seen that a decided leverage action is asserted by inward pressure upon the upstanding laminations of the wall and the lasting margin of the upper so that the fine lines of the last are brought out in the upper to a much greater extent than has been possible in slip lasting methods heretofore practised. Preferably and as herein shown, the lasting margin of the upper is skived on its outer surface before being attached to the upstanding wall of the insole. This results in the formation of a smooth bottom when the laminations of the wall and lasting margin of the upper are folded down and secured in flat condition to the insole, and a bottom to which an outsole may be conveniently secured by cement.

The novel process of my invention may be practised with great advantage in the production of welt shoes in that the upstanding wall and margin of the upper are presented in ideal condition for the attachment of a welt. Accordingly, in producing a welt shoe, the welt may be conveniently placed next to these upstanding laminations and secured thereto by stitching or stapling. Then, as before, the upstanding laminations together with the inner margin of the welt are folded inwardly over the last bottom and adhesively secured to it. This folding operation tends to throw the outer margin of the welt into the horizontal position required for outsole stitching and, as before, the upper is subjected to an effective lasting operation about its entire periphery.

These and other features of the invention will be best understood and appreciated from the following description of a preferred manner of practising the invention as illustrated in the accompanying drawings in which:

Fig. 1 is a view in perspective of an insole showing its wall or flange partially pulled away from the edge.

Fig. 2 is a view in perspective showing the insole and an upper preparatory to being united.

Fig. 3 is a view in perspective showing the lasting margin of the upper as adhesively united to the upstanding wall of the insole.

Fig. 4 is a view in perspective of the upper upon an inserted last.

Fig. 5 is a fragmentary view on an enlarged scale showing the relation of the folded laminations of the wall and upper to the insole,

Figs. 6 and 7 are views in perspective corresponding to Figs. 3 and 4 showing a welt in position upon the upper.

Fig. 8 is a fragmentary view corresponding to Fig. 5 showing the relation of the upstanding

laminations of the wall and upper to the insole, that is to say, the position of these parts before they are folded, and

Fig. 9 is a fragmentary view illustrating the construction of a welt shoe as completed from the parts shown in Figs. 6 and 7.

One of the important advantages of my improved process is apparent at once from a consideration of the insole employed. It requires no channelling, lip-turning or reinforcing but comprises merely a thin flat blank 10 which may be of any suitable insole leather or stiff fibrous material not over three or four irons in thickness. An upright wall 11 that is self-sustaining is erected about the edge of the insole blank 10 preferably consisting of a binding tape or textile strip adhesively coated, folded upon itself and provided with an inner flange 12 which is secured to the inner face of the blank 10, and another flange 13 which is secured to the outer face of the blank 10. The binding strip may be homogeneous or, as shown in Fig. 1, it may comprise a composite strip of two materials secured together by zig-zag stitching. In some cases the inner portion including the flange 12 may be a textile adhesive tape while the remainder of the wall or flange may be of fibrous composition. In any case the wall is applied progressively about the edge of the blank 10 and its ends butted. The wall or flange is substantially flush at its lower edge with the inner face of the insole, that is to say, the face which is lowermost in Fig. 1 or next the wearer's foot in the finished shoe. The insole may be prepared entirely in the stock fitting department and comes to the making room in the condition shown in Fig. 2.

Meanwhile the upper 14 is pre-formed in the stitching room so that its peripheral contour exactly fits the contour of the wall 11 of the insole. Preferably and as herein shown, the lasting margin of the upper is skived to provide a zone 15 which is thus slightly reduced in thickness and give a surface particularly well adapted to take an adhesive coating.

The next step of the process consists in adhesively uniting the lasting margin of the upper to the upstanding portion of the outer surface of the upright wall 11. This may be conveniently done by hand or with the assistance of a support for holding the flanged insole while the margin of the upper is progressively brought into the proper location and caused to adhere by pressure to the wall. The condition of the partially formed shoe at this stage is indicated in Figs. 3 and 8 and from these it will be seen that the wall 11 of the insole and the lasting margin of the upper project upwardly above the outer face of the insole 10 and substantially at right angles thereto, with the marginal edge of the upper terminating substantially flush with the upper edge of said wall.

The process has now been carried to the point where the upper is ready to receive the last, and accordingly the proper last 16 is now forced into the upper. This operation is usually carried out on a hinged last which is spindled on a vertical pin in collapsed condition with its toe portion projecting upwardly at about 45°. The toe of the upper is usually mulled to soften the box toe material and in this condition the upper is pulled on to the last. The toe portion of the last is then swung downwardly, the last elongated and latched in position holding the upper under considerable longitudinal stress and causing it to conform to the surface contour of the last.

The next step of the process consists in forceably folding inwardly the laminations of the wall 11 together with the lasting margin 15 of the upper and securing these laminations as a unit 5 in flat condition upon the outer face of the insole. At this stage of the process the last 16 provides a solid body within the upper and the upstanding laminations of the united wall and upper are conveniently positioned and held in 10 place to receive a substantial inward pressure which, with a continuous leverage action, places the upper 14 under substantial lasting strain. The folded over laminations may be flattened down and caused to adhere securely to the insole 10 by pressure or by pounding, and these parts now occupy the position shown in Fig. 5.

Having brought the shoe to the condition indicated in Figs. 4 and 5 the bottom may be filled and an outsole laid and attached by cement or, if the last is withdrawn, by Littleway or McKay stitching.

The process of my invention is illustrated in its application to the manufacture of welt shoes in Figs. 6, 7 and 9. In Fig. 6 the lasted margin 25 24 of the upper 25 is shown as adhesively attached to the upstanding wall 11 of the insole. A welt 26 is shown as secured by staples 27 to the upstanding laminations of the lasting margin 24 and the wall 11. In Fig. 6 the last 16 is shown as 30 already inserted in the upper, but it will be understood that the welt 26 may be secured to the upper either before or after the last is inserted and that instead of by staples the welt 26 may be sewed to the upper by conventional inseam 35 sewing machine or otherwise.

In Fig. 7 the partially completed shoe is shown as having the laminations of the lasting margin of the upper and wall 11 folded inwardly, flattened down and adhesively secured to the surface of the insole 10, and in this operation as before the upper is subjected to a substantial lasting strain created and augmented by the leverage action of infolding pressure on the upstanding laminations of the unified upper and wall 11. In this operation the outer portion of the welt 26 is brought into approximately horizontal position about the periphery of the shoe and ordinarily will not require any supplementary welt beating to position it for the outsole lock-stitching step.

As suggested in Fig. 9, the bottom of the shoe may be completed by the application of a filler 28 between the overlasted margins of the upper, the laying of an outsole 29, and an outsole stitching operation by which an outseam 30 is formed to unite the welt 26 and the outsole 29.

The wall 11 of the insole is shown in an enlarged scale in Figs. 5, 8 and 9. Its essential characteristics are that it must be flexible so that it may be easily folded about a vertex adjacent to the outer peripheral edge of the insole 10 and at the same time stiff enough as a whole to resist crushing. Having these characteristics it will be seen that the wall acts as a lever to overdraw the attached lasting margin 15 of the upper when it is forceably folded inwardly through an angle of about 90° and into contact with the insole surface. In Figs. 5 and 8 the heavy black line 17 indicates the area of cement uniting the wall 11 and the lasting margin 15 and it will be noted that this terminates opposite the outer edge face of the insole 10, leaving the upper below that point free to move under the lasting stress. The edge of the relatively stiff insole acts as a fulcrum about which

the upstanding united plies of the upper and wall are folded and over which the unsecured portion of the upper is drawn.

While there are advantages in supporting the upper internally by an inserted last, shoes may be produced in accordance with the process of my invention without the assistance of a last at any time. For example, it is necessary to support the upper only temporarily and only at the point in its periphery where its upstanding margin is being folded inwardly with the insole flange above the insole. Such support may be furnished by a horn, jack or rest shaped to enter the inner angle between the upper and the insole and past which the shoe may be moved as the folding step is progressively carried out.

The upper may include an open or closed vamp, or it may be in the form of straps as in a strap sandal. Accordingly, the term "upper" is used herein in a broad sense to cover such constructions. It will be apparent also that in uniting the margin of the upper to the upstanding flange of the insole cement, staples, stitching or tacks may be used as best suited to the particular work in hand, all within the scope of the present invention. Also, if desired, the toe and heel ends of the upper may be preformed by molding before being attached to the upstanding flange of the insole. In some cases, moreover, the flanged sole may be incorporated in the shoe as a mid-sole and for purposes of the present invention should be considered as an equivalent of the insole specifically shown and described herein.

Having thus disclosed my invention and described in detail a preferred embodiment thereof, I claim as new and desire to secure by Letters Patent:

1. The process of making lasted shoes which comprises providing a stiff insole having a flexible, easily folded upstanding wall that is stiff enough to resist crushing bound to its peripheral edges by flanges attached to the upper and lower flat faces of the insole, said wall extending in substantial alignment with the peripheral edge face of said insole, adhesively attaching the marginal edge of an upper to only, and through-

out, the upstanding portion of the outer face of said wall with said edge terminating substantially flush with the upper edge of said wall, inserting a last in the upper, forceably folding the wall with the attached marginal edge of the upper inwardly over the exposed face of the insole while supported by the last and thereby drawing the adjacent unattached portion of the upper over the edge of the insole, and securing the folded wall with the attached marginal edge of the upper to the exposed face of the insole.

2. The process of making lasted shoes which comprises providing a stiff insole that has bound to its edge portion a preformed, self-sustaining upstanding wall that is stiff enough as a whole to resist crushing, and flexible enough to be folded smoothly, said wall extending in substantial alignment with the peripheral edge face of said insole and enclosing a sole-shaped area, attaching the lasting margin of an upper only to the outer face of the upstanding portion of the wall with the edge of said lasting margin terminating substantially flush with the upper edge of said wall, inserting a last in the upper, forceably folding the wall with the attached margin of the upper inwardly over the exposed face of the insole including the toe portion thereof while the latter is supported by the last and thereby drawing the adjacent unattached portions of the upper over the edge of the insole, and securing the folded wall directly throughout its full width to the exposed face of the insole with the attached margin of the upper overlying the folded wall and separated from the insole by the single thickness of the wall.

ARTHUR E. KLEVEN.
